[57] **CLAIM**

The ornamental design for an offset adaptor for an orthopaedic driver instrument, as shown and described.

DESCRIPTION

FIG. 1 is a perspective view of an offset adaptor for an orthopaedic driver instrument;

FIG. 2 is a side elevation view thereof;

FIG. 3 is an end elevational view thereof;

FIG. 4 is a side elevational view thereof of the side opposite the side shown in FIG. 2;

FIG. 5 is an end elevational view thereof of the end opposite the end shown in FIG. 3;

FIG. 6 is a top plan view thereof;

FIG. 7 is a bottom plan view thereof;

FIG. 8 is a perspective view of an second embodiment of an offset adaptor for an orthopaedic driver instrument;

FIG. 9 is a side elevational view thereof;

FIG. 10 is an end elevational view thereof;

FIG. 11 is a side elevational view thereof of the side opposite the side shown in FIG. 9;

FIG. 12 is an end elevational view thereof of the end opposite the end shown in FIG. 10;

FIG. 13 is a top plan view thereof; and,

FIG. 14 is a bottom plan view thereof.

The broken line showing in FIGS. 1–14 is for illustrative purposes only and forms no part of the claimed design.
